UNITED STATES PATENT OFFICE.

WILLIAM E. HALE, OF FORT WASHINGTON, PENNSYLVANIA, ASSIGNOR TO R. H. BEAUMONT COMPANY, OF PHILADELPHIA, PENNSYLVANIA, A CORPORATION OF PENNSYLVANIA.

DRAG-SCRAPER.

1,377,830.

Specification of Letters Patent.

Patented May 10, 1921.

Application filed February 7, 1920. Serial No. 357,096.

To all whom it may concern:

Be it known that I, WILLIAM E. HALE, a citizen of the United States, residing in Fort Washington, Montgomery county, 5 Pennsylvania, have invented certain Improvements in Drag-Scrapers, of which the following is a specification.

My invention relates to certain improvements in scrapers used in handling coal and 10 other granular material. In this type of apparatus, the coal is discharged into a hopper and carried by a scraper onto a piling floor, or from the pile on the floor to a discharge point.

15 The object of my invention is to improve the construction of the scraper so that it will readily fall back in returning after pushing the load forward, while the bail remains in substantially a horizontal position. The 20 invention also relates to certain details which will be fully described hereinafter.

In the accompanying drawings:

Figure 1 is a diagrammatic side view, illustrating one form of apparatus for 25 handling material using a drag scraper.

Fig. 2 is an enlarged side view of my improved drag scraper, showing in the position it assumes in pushing a load.

Fig. 3 is a plan view;

30 Fig. 4 is a side view showing the scraper in the position which it assumes in returning after delivering a load;

Fig. 5 is a detached end view of one of the clamps used in connection with the scraper; 35 and

Fig. 6 is a sectional view on the line 6—6, Fig. 5.

1 is a rope which passes from mechanism in a machinery house *a* around suitable 40 sheaves and around a back sheave 2 secured to a back post 3 at the opposite side of the piling floor 4 to that of the machinery building and hopper 5. In the present instance, I have illustrated in diagram the means for 45 discharging coal from a car and the means for elevating the coal to a bunker, the piling floor being so located that coal may be scraped from the pile of coal *a* into the hopper 5, or can be discharged from a chute 6 50 connected to an elevator 7 onto the pile, the scraper being arranged so as to distribute it over the pile.

The above described method is one method

of handling coal and like material by means of a drag scraper.

55 Referring to Figs. 2 and 3, 10 is a scraper made of sheet metal having a body portion 11 curved at the upper end 12 and having side portions 13. The scraper is open at the bottom and at the front and has a series of 60 teeth 14 extending below the bottom so as to penetrate the body of coal over which it passes. Attached at each side to the lower end of the scraper are plates 15 connected to the side portions by braces 16. 17 are 65 pivot pins for a bail 18, the two members of the bail being angular and extending to a point in front of the scraper. This bail is pivoted to a shackle 19 by a vertical pin 20 and pivotally connected to the shackle are 70 links 21 to which the rope clamp 22 is pivoted so that the rope clamp is free to swing according to the tension on the rope. The shackle 19 is connected by a chain 23 to another rope clamp 24 which, in turn, is 75 connected by two chains 25 to eyes 26 at the rear of the scraper. The rope 1 passes over the scraper and is attached to the clamps 22 and 24, as shown, there being sufficient slack in the rope between the two clamps to 80 allow the clamp 24 to assume the position shown in Fig. 4, when the scraper is returning to engage another load. By this construction the scraper can be clamped to the rope at any point desired.

85 I have illustrated the clamp 22 in detail in Figs. 5 and 6, the clamp 24 being a duplicate of the clamp 22. The clamp 22 consists of a U-shaped plate 30 having side members 27 which are hooked at their outer ends 32. 90 A fixed member 31 is mounted on a bolt 28 within the U-shaped plate. 35 is the movable member adapted to slide on the U-shaped plate; a clamp screw 34 passes through a nut 33 swiveled in the hooked end 32 of the plate and bears upon the movable member. The fixed member 31 of the clamp is V-shaped and the movable member 35 is shaped to correspond to the fixed member so that, when the screw is applied, the rope is 100 clamped firmly between the two members and kinked so as to hold it rigidly in position. The bolt 28 is the pivot bolt by which the clamp is attached to the links 21.

105 By the above construction, it will be seen that a single rope can be used and the scraper

can be attached to the rope at any point desired by the clamps.

The operation is as follows:—When the scraper is attached to the ropes, as shown in Fig. 2, and power is applied, the rope drags the scraper forward and the coal, or other material will be collected in front of the scraper as it moves forward and will automatically flow from the scraper when 10 the end of the pile is reached, or when the forward movement of the scraper is discontinued the coal is left at this point on the pile. Then the mechanism is reversed and the scraper is drawn back over the pile, the 15 scraper falling back, as in Fig. 4, so that it will ride over the surface of the coal the same as a sled. Then, when it has reached the point desired, the mechanism is again reversed and the scraper is moved forward, 20 the teeth in the scraper engaging the coal and the first movement will be to elevate the scraper to the position illustrated in Fig. 2, when it will collect material by pushing the material forward. By pivoting the bail, 25 as shown, the scraper is free to assume the two positions mentioned above.

While I have shown chains 23 connecting the clamp plate 24 to the bail of the scraper, this chain may be omitted in some instances, 30 but is essential where two ropes are used, one connected to the bail and the other to the rear of the scraper.

I claim:—

1. The combination in a scraper for handling granular material, of a body portion 35 open at the front and at the bottom; a bail pivoted to the body portion at or near the bottom and extending in front of the scraper; and a rope connected to the bail and to the rear of the scraper so that the bail 40 remains in substantially a horizontal position when the body portion is in a vertical or a horizontal position.

2. The combination of a scraper for handling granular material consisting of a body 45 portion curved at its upper edge and having side members; a bail pivotally connected to the lower end of the side members; clamps connected to the bail and to the body portion at the back of the scraper; and a rope 50 attached to the bail by the clamps.

3. The combination of a scraper consisting of a body portion curved at the upper edge; two side members; plates at the lower end of each side member; a bail pivotally 55 connected to the plates; a shackle pivotally connected to the bail; a rope clamp attached to the shackle; a second rope clamp; a chain connecting the second rope clamp with the rear of the scraper; and a rope extending 60 through both clamps and slack between the clamps.

WILLIAM E. HALE.
